UNITED STATES PATENT OFFICE.

EMIL STRANSKY, OF WARREN, PENNSYLVANIA, ASSIGNOR TO FRANK B. RAE, JR.,
AND E. G. K. MEISTER, BOTH OF CLEVELAND, OHIO.

ELECTRICALLY-HEATED FLATIRON.

Application filed December 8, 1921, Serial No. 520,970. Renewed August 1, 1923.

To all whom it may concern:

Be it known that I, EMIL STRANSKY, a citizen of the United States, residing at Warren, in the county of Warren and State 5 of Pennsylvania, have invented new and useful improvements in Electrically-Heated Flatirons, of which the following is a specification.

One object of my said invention is the 10 provision in a flat iron of the type indicated of improved means for automatically regulating the heating of the base member of the iron with a view to averting scorching of materials being ironed.

Another object of the invention is the 15 provision of a flat iron of improved general construction, designed more especially to render it feasible to renew impaired parts with facility so that loss of the entire iron 20 is avoided.

To the attainment of the foregoing and other objects hereinafter developed the invention consists in the improvement as hereinafter described and definitely claimed.

25 In the accompanying drawings, forming part of this specification:—

Figure 1 is a view showing an iron constructed in accordance with my invention ready for use.

30 Figure 2 is a top plan view of the iron as it appears when the cap shell is removed.

Figure 3 is a longitudinal vertical section taken in the plane indicated by the line 3—3 of Figure 2.

35 Figure 4 is an enlarged detail view of the thermostat of my invention employed in the base member of the iron.

Figures 5 and 6 are longitudinal vertical 40 sections of modifications hereinafter explicitly referred to.

Figure 7 is a diagram of the electrical connection.

Similar numerals designate corresponding 45 parts in Figures 1 to 4 and 7 to which reference will first be made.

Among other elements my novel flat iron 50 comprises a cap shell 1 having an aperture 2 for the passage of an attaching screw 3, and also having a sleeve 4 for the passage of wires 26 and 28, designed to be appropriately connected with a source of electric energy. On the said cap shell 1 is a

handle 6 which may be connected or engaged therewith in any appropriate manner.

In addition to the elements stated the 55 iron comprises a base member 7 with an ironing surface 8, and a body member 9, the said base member 7 and the body member 9 being preferably of cast iron.

In the upper side of the base member 7 60 is a recess 10, and carried on the upper side of the base member 7 is a body 11^x of appropriate dielectric material such as dielectric cement, mica or the like in which is carried a resistance or heating element 12. 65 Manifestly when the said heating element 12 is impaired, the base member 7, the dielectric material 11^x and the heating element 12 may be removed as a unit and replaced with a fresh base member 7 bearing dielectric material 11^x and a heating element 12. 70

An important feature of my invention resides in the thermostat or thermostatic switch best shown in Figure 4, and the arrangement of said switch relative to the 75 base member 7 and the heating surface thereof. The said thermostatic switch is located in the recess 10 of the base member 7 so as to be thoroughly amenable to the temperature of the said member 7. The 80 thermostatic switch illustrated and which I have successfully used in actual practice is made up of a bar 11, a bar 12^x spaced from the bar 11, a body of insulating material 13 interposed between and connected with the 85 bars 11 and 12^x, a thin metallic strip 14 superimposed on the bar 11 and also connected with the body of insulation 13, a contact protuberance 15 at the underside of the free portion of the bar 12^x, and a screw 90 16 adjustably connected with the free portion of the bar 11 and having a head adapted to engage the free end of the thin strip 14 and cooperate therewith for a purpose hereinafter set forth. At this point I would have it understood that the bar 11 is composed of two metals 17 and 18 one of which is less amenable to the action of heat than the other, this in order to render the bar more prompt in action; also, that the lower 95 member 18 is transversely kerfed at its underside as indicated by 19 so that strain is taken off the connecting screw 20 incident to bending of the bar 11. The thin strip 14

100

is possessed of resiliency, and is normally arranged against the contact protuberance 15, it being understood in this connection that the bars 11 and 12^a are interposed between and electrically connected with the heating element 12 and the source of electric energy. With this understanding, it will be further understood that when the base member 7 is heated to a predetermined extent, the heat of the said member 7 will have the effect of causing the free portion of the bar 11 to move away from the free portion of the bar 12^a so that the head of the screw 16 will engage and draw the strip 14 out of contact with the protuberance 15. In this way the supply of current to the heating element 12 will be cut off until the temperature of the base member 7 is reduced to a predetermined extent when the bar 11 will be restored to its normal state, and incident to such restoration the strip 14 will be carried against the protuberance 15 and the supply of current to the heating element 12 will be reestablished. From this it follows that my novel thermostatic switch will reliably maintain the temperature of the base member 7 at a uniform degree so that the said member 7 during the use of the iron will operate efficiently, and yet there will be no liability of the said member 7 being unduly heated so that the fabric being ironed will be scorched.

The thermostatic switch is connected with the body member 9, and is removable with the said body member 9 as a unit, it being understood in this connection that the body member 9 is detachably connected with the base member 7 through the medium of screws 21, although other means may be employed for the detachable connection without affecting my claimed invention.

The terminal of the lower bar 11 of the described switch is designated by 22, and the terminal of the upper switch bar 12^a is designated by 23. The said terminals 22 and 23 are extended upwardly through the body member 9.

With a view to reducing to a minimum arcing between the contacts of the described thermostatic switch I provide a condenser 24 which per se may be of any construction compatible with the purpose of my invention.

By particular reference to Figures 2, 3 and 7 it will be observed that the terminal 22 is electrically connected through wire 26 with one side of the source of energy, designated by 25, and that the terminal 23 is electrically connected by wire 27 with the heating element 12 which, in turn, is electrically connected by wire 28 with the opposite side of the source of energy; also, that the condenser 24 is electrically coupled across the thermostatic switch to accomplish the purpose before indicated. In the preferred em-

bodiment of my invention the condenser 24 is superimposed on the forward portion of the body member 9 and is appropriately connected therewith.

In the modifications illustrated in Figures 5 and 6 the heating element 12^a is embedded in dielectric cement 11^a which is carried on and by the base member 7^a, and the condenser 24^a is arranged above and carried by the central portion of the body member 9^a. It will also be observed that the thermostatic switches shown in Figures 5 and 6 lack the screw 16 before described. In lieu of the said screw 16 the bar 11^a in each of the said switches has at its free end a hook 16^a which is designed to cooperate with the thin strip 14^a in the same manner that the head of the screw 16 cooperates with the thin strip 14. It will also be noted by particular reference to Figure 5 that the bars 11^a and 12^a have terminals 22^a and 23^a arranged as shown relative to a body of insulation 13^a, and that the said bars 11^a and 12^a are connected together though insulated from each other at 20^a.

The thermostatic switch in Figure 6 has the bar 11^b arranged above the bar 12^b, and the insulation body 13^b and the terminals 22^b and 23^b are arranged as illustrated as is also the connecting means 20^b. It will be understood, however, that the operation of each of the modifications in Figures 5 and 6 is generally similar to the operation of the embodiment shown in Figures 1, 2 and 3, and that the modifications are possessed of all of the practical advantages hereinbefore ascribed to the embodiment in Figures 1 to 3.

In each of the constructions it will be noted that the heating element in its dielectric is separated from the space, in which is mounted the thermostatic switch, by a portion of the body of the iron. In Fig. 3 the separate flange being integral with the body member 9, and in the form shown in Figs. 5 and 6 is a separating flange, shown as integral with the body member 7^a, the result of which is to prevent any direct radiation of heat from the heating element to the thermo-responsive element.

I have entered into a detailed description of the construction and relative arrangement of the parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope of my invention as defined in my appended claims.

Having described my invention, what I

claim and desire to secure by Letters-Pat-
ent, is:—

1. An electrically-heated flat iron comprising a base member recessed at its upper side, a heating element carried in dielectric material at the upper side of said base member, a body member connected with and separable from the base member, a thermostatic switch carried by the body member and disposed in the said recess of the base member, and a condenser superimposed upon and carried by the body member and electrically coupled across the thermostatic switch. 50
2. In an electrically-heated flat iron, the combination of a base member with an ironing surface and also with a recess in its upper side, a body member detachably connected with and separable from the base member, a heating element carried in dielectric material on the base member, a thermostatic switch carried by the body member and disposed in said recess of the base member and having bars and a thin strip between the bars and electrically connected with one of the same and also having on one of the bars means to engage said thin strip and break the contact between the same and the other bar, and a condenser carried by the body member and electrical- 55
3. In an electrically-heated flat iron, the combination of a base member with an ironing surface and also with a recess in its upper side, a body member detachably connected with and separable from the base member, a heating element carried in dielectric material on the base member, a thermostatic switch carried by the body member and disposed in said recess of the base member and having bars and a thin strip between the bars and electrically connected with one of the same and also having on one of the bars means to engage said thin strip and break the contact between the same and the other bar, and a condenser carried by the body member and electrically coupled across the thermostatic switch. 60
4. An electrically heated flat iron comprising a plurality of body members, ar- 55
5. In an electric flat iron, the combination of a plurality of members forming the body and base of the iron, and arranged to pro- 65
6. An electrically heated flat iron comprising a plurality of body members ar- 80
7. In an electric flat iron, the combination of a plurality of members forming the body and base of the iron, and arranged to pro- 70
8. An electrically heated flat iron comprising a plurality of body members ar- 85
9. In an electric flat iron, the combination of a plurality of members forming the body and base of the iron, and arranged to pro- 75
10. An electrically heated flat iron comprising a plurality of body members ar- 90

across the thermostatic switch; one of the bars of the thermostatic switch being composed of metals one of which is less amenable to the action of heat than the other, and having in one of the metallic portions a transverse kerf. 50

4. An electrically heated flat iron comprising a plurality of body members, ar- 55

5. In an electric flat iron, the combination of a plurality of members forming the body and base of the iron, and arranged to pro- 65

6. An electrically heated flat iron comprising a plurality of body members ar- 80

7. In an electric flat iron, the combination of a plurality of members forming the body and base of the iron, and arranged to pro- 70

8. An electrically heated flat iron comprising a plurality of body members ar- 85

9. In an electric flat iron, the combination of a plurality of members forming the body and base of the iron, and arranged to pro- 75

10. An electrically heated flat iron comprising a plurality of body members ar- 90

5. In an electric flat iron, the combination of a plurality of members forming the body and base of the iron, and arranged to pro- 65

6. An electrically heated flat iron comprising a plurality of body members ar- 80

7. In an electric flat iron, the combination of a plurality of members forming the body and base of the iron, and arranged to pro- 70

8. An electrically heated flat iron comprising a plurality of body members ar- 85

9. In an electric flat iron, the combination of a plurality of members forming the body and base of the iron, and arranged to pro- 75

10. An electrically heated flat iron comprising a plurality of body members ar- 90

5. In an electric flat iron, the combination of a plurality of members forming the body and base of the iron, and arranged to pro- 65

6. An electrically heated flat iron comprising a plurality of body members ar- 80

7. In an electric flat iron, the combination of a plurality of members forming the body and base of the iron, and arranged to pro- 70

8. An electrically heated flat iron comprising a plurality of body members ar- 85

9. In an electric flat iron, the combination of a plurality of members forming the body and base of the iron, and arranged to pro- 75

10. An electrically heated flat iron comprising a plurality of body members ar- 90

In testimony whereof I affix my signature.

EMIL STRANSKY.
